UNITED STATES PATENT OFFICE

95,156

DESIGN FOR A VENDING MACHINE CABINET

Oscar D. Soellner, Chicago, Ill., assignor to Exhibit Supply Co., Chicago, Ill., a corporation of Illinois

Application February 11, 1935, Serial No. 55,339

Term of patent 7 years

To all whom it may concern:

Be it known that I, Oscar D. Soellner, a citizen of the United States, residing at Chicago, in the county of Cook and State of Illinois, have invented a new, original, and ornamental Design for a Vending Machine Cabinet, of which the following is a specification, reference being had to the accompanying drawing, forming part thereof, and in which:

The single figure is a perspective view of a vending machine cabinet showing my new design.

I claim:

The ornamental design for a vending machine cabinet as shown.

OSCAR D. SOELLNER.
